(57) **CLAIM**

The ornamental design for a beverage container as shown and described.

DESCRIPTION

FIG. 1 is a top perspective view of a beverage container illustrating our ornamental design;

FIG. 2 is a bottom perspective view thereof;

FIG. 3 is a first elevation view comprising a rotational angle view about a central-common axis extending axially from the center of the bottom to the center of the top of the beverage container in views of FIGS. 1 and 2 from zero degrees to ninety degrees;

FIG. 4 is a top plan view thereof;

FIG. 5 is a bottom plan thereof;

FIG. 6 is a second elevation view comprising a rotational angle view about a central-common axis extending axially from the center of the bottom to the center of the top of the beverage container in views of FIGS. 1 and 2 from ninety degrees to one-hundred and eighty degrees;

FIG. 7 is a third elevation view comprising a rotational angle view about a central-common axis extending axially from the center of the bottom to the center of the top of the beverage container in views of FIGS. 1 and 2 from one-hundred and eighty degrees to two-hundred and seventy degrees;

FIG. 8 is a fourth elevation view comprising a rotational angle view about a central-common axis extending axially from the center of the bottom to the center of the top of the beverage container in views of FIGS. 1 and 2 from two-hundred and seventy degrees to three-hundred and sixty degrees; and,

FIG. 9 is an elevated sectional view of FIG. 4 about section lines 9-9.

The dashed lines or dot lines are for environmental purposes and form no part of the ornamental design. The leader lines in FIG. 4 are section lines and form no part of the ornamental design.

1 Claim, 4 Drawing Sheets
